L. G. MILLER,
CAR REINFORCEMENT AND DOOR HINGE.
APPLICATION FILED FEB. 18, 1921.

1,377,716.

Patented May 10, 1921.

UNITED STATES PATENT OFFICE.

LOUIS G. MILLER, OF WESTMONT BOROUGH, PENNSYLVANIA.

CAR-REINFORCEMENT AND DOOR-HINGE.

1,377,716.

Specification of Letters Patent. Patented May 10, 1921.

Application filed February 18, 1921. Serial No. 446,059.

To all whom it may concern:

Be it known that I, LOUIS G. MILLER, a citizen of the United States, and a resident of the borough of Westmont, in the county of Cambria and State of Pennsylvania, (whose post-office address is Johnstown, Pennsylvania,) have invented certain new and useful Improvements in Car-Reinforcements and Door-Hinges; and I do hereby declare the following to be a full, clear, and exact description of the invention, such as will enable others skilled in the art to which it appertains to make and use the same.

My invention relates to the construction of cars and particularly of metal cars, and consists generally of a construction whereby the car floor or the car hopper adjacent to the discharge doors is strengthened and reinforced by a metal member secured to or near the edge, and which in addition to serving as a strengthening member is also so constructed that it serves as a portion of the hinge on which the door operates. By combining these two features, I make a construction which is lighter, cheaper and more efficient than if these were separate items, as the weight and labor involved in my construction is less while its strength and usefulness is maintained.

Another advantage of my construction is that the reinforcing and hinge member is made from a bar which may be rolled in a rolling mill of steel or other metal best adapted to serve the combined purposes. The use of my combined member will minimize the amount and cost of stiffening and strengthening a car floor or the hopper sheets thereof adjacent to the door opening, thereby providing the required rigidity without the use of unnecessary parts, and my construction is also simple, economical and efficient.

Referring now to the annexed sheet of drawings which forms a part of this specification:—Figure 1 is a vertical longitudinal sectional elevation through the hopper and doors of a portion of a car taken on the line I—I of Fig. 2. Fig. 2 is a vertical transverse sectional elevation taken on the line II—II of Fig. 1. Fig. 3 is a detail view illustrating in top plan and side elevation one of my forms of car door hinge. Fig. 4 is a detail view in side and end elevation of one of the hinge filler blocks. Fig. 5 is an enlarged detail sectional elevation of a portion of the car hopper and door taken on

the line I—I of Fig. 2. Fig. 6 is a side elevation of one form of my rolled hinge and reinforcing bar. Fig. 7 is a top plan view of the rolled bar illustrated in Fig. 6. Fig. 8 is one form of rolled bar which I prefer to use in connection with the car hopper of the type of car illustrated, this being known as the H-25 type of car in which the doors when closed are arranged at a slight angle from the horizontal as shown, and the hopper sheets are also arranged at a comparatively small angle. Fig. 9 is another modification of the rolled bar which I prefer to use in connection with flush bottom gondola cars in which the doors are substantially continuations of the car bottom or below and approximately parallel thereto, and Fig. 10 is the cross-section of another slightly modified form of bar also adapted for this purpose. Fig. 11 is another modified form of section of rolled bar which may be used for the same purpose as the bar illustrated in Fig. 8. Fig. 12 is a cross-section of another modified form of bar from which I can produce a combined reinforcing and hinge bar which is particularly adapted to cars of the hopper type with doors which when closed are more nearly upright and the hoppers of which have a steeper slope, this being known as the G.L.A. type of car. Fig. 13 is an illustration of another form of car door hinge which has a bifurcated end portion, but on account of the simplicity of manufacture, I may prefer to use the form of hinge strap illustrated in Fig. 3 in connection with the hinge filler blocks.

Although I have illustrated my invention in connection with a certain type of hopper car known as the H-25, I wish it understood that it can be used in connection with any type of car which is provided with door openings and doors.

Referring now to the characters of reference on the drawings:—1 illustrates a portion of a metal car, 2 are the side hopper sheets thereof, 3 is the central ridge covering the center sills, 4 and 5 are the transverse hopper sheets, 6 is the base flange or one leg of one form of rolled bar from which to form my reinforcing and door hinge member, this being the form illustrated in Figs. 1, 2, 5, 6, 7 and 8. 7 is the web or other leg portion of the bar illustrated in Fig. 8 and the portion 6 has another shorter flange projecting from the other side of the web as illustrated, one of these flanges preferably

having a rounding on its under side while the shorter one has a rounding on its upper side which in connection with the edges of the transverse hopper sheets forms an inclined surface adapted to allow the material in the car to be discharged readily therefrom without interference. 8 is the bulb edge, the outstanding portion of which is substantially of circular section. 9 are slotted holes which are punched or otherwise formed in the web portion and adapted to receive the end 12 of the door hinge, as illustrated in Fig. 3, or one of the ends 18 of the door hinge as illustrated in Fig. 13, this arrangement being shown in Figs. 1, 2, 3 and more clearly shown on a larger scale in Fig. 5, which latter figure shows the door hinge strap of Fig. 3 in connection with the hinge filler blocks 13. The holes 9 may be punched through the web or leg and if desired the fins so formed may be removed by filing or otherwise tooling so that the portion of the bulb 8 adjacent to the slots 9 is circular in section to enable the hinge strap to rotate freely thereon. The car doors, which are shown as of pressed metal, are 10. 11 is my preferred form of car door hinge having the bent end portion 12, the curve between the portions 11 and 12 being of such size and conformation as to fit neatly over the bulb portion 8 of the bar adjacent to the slots 9. 13 are hinge filler blocks, which may be made of any kind of metal in the shape shown and adapted to be riveted or bolted in place between the leg 12 and the flange 15 of the car door, this connection being shown as a rivet 14 in Figs. 1, 2 and 5.

In order to make a neat construction and to have the hinge strap on the lower surface 40 of the door I provide an opening or slot 16 in the pressed steel door, through which the leg 11 of the hinge strap is inserted, which strap is bolted or riveted to the under side of the car door as illustrated.

45 Referring to Fig. 13, 17 is a modified form of car door hinge strap which has a pair of legs 18 formed integral in order to provide a bifurcation, the size and curvature between its two legs being such that they 50 are adapted to fit over and rotate upon the bulb portion of the hinge bar adjacent to the slots 9.

As illustrated in Fig. 8 this bar is of angular form with one long upper leg attached 55 to the car side and one much shorter adjacent to the door opening, with another leg or web 7 and integral portion 8.

Referring to Fig. 9, this form of bar is of Z-shape and has a web portion 19 and a 60 bulb portion 20, while as illustrated in Fig. 10 this type of bar is of an obtuse angular form having the web or leg portion 21 and another leg or flange portion inclining downwardly therefrom and provided with the bulb portion 22.

The form of bar illustrated in Fig. 11 is of angular shape, having the legs 23 and the bulb portion 24, while the shape illustrated in Fig. 12 is of T-bar of bulb beam shape, having the flanges 25 and web connecting these with the bulb 26. 70

Although I have described and illustrated my invention in considerable detail, I do not wish to be limited to the exact and specific details thereof, as shown and described, 75 but may use such modifications in, substitutions for, or equivalents thereof, as are embraced within the scope of my invention, or as pointed out in the claims.

Having thus described my invention, what 80 I claim and desire to secure by Letters Patent is:—

1. A reinforcing bar of angular section secured by one of its legs or flanges to a car bottom adjacent to the door opening thereof, one of its legs or flanges being provided with a bulb of substantially circular section, integral with the rest of the bar, adapted to form one member of the door hinge. 85

2. A reinforcing bar of angular section 90 secured to a car floor near the door opening thereof by one of its legs or flanges, another of its legs being provided with a bulb of substantially circular section, integral with the rest of the bar, and slots 95 through the leg adjacent to said bulb adapted to receive the door hinge straps.

3. A reinforcing bar one portion of which is secured to a car bottom adjacent to the door opening thereof, the opposite portion 100 being provided with a bulb of substantially circular section integral with the rest of the bar, and slots through the body adjacent to said bulb adapted to receive the door hinge straps. 105

4. A reinforcing bar of angular section one of the legs of which is secured to a car bottom adjacent to the door opening thereof, the bar having another and shorter leg extending oppositely from the leg aforesaid 110 and provided with a rounding on its upper surface adjacent to the edge of the door opening, the downwardly extending leg of said bar being provided with an integral bulb of substantially circular section, and 115 slots in the latter leg adjacent to said bulb adapted to receive the door hinge straps.

5. The combination with a car having an opening in the floor thereof, of an angular reinforcing bar one leg of which is secured 120 to the car bottom adjacent to said opening, the other leg being provided with a bulb of substantially circular section integral with the rest of the bar, slots through said leg adjacent to the bulb and door hinge 125 straps, the ends of which pass through said slots and are adapted to rotate on said bulbs.

6. In a metal car, the combination with a reinforcing bar, secured to the car floor adjacent to the door opening thereof, said 130

bar being provided with a bulb of substantially circular section and slots in the body thereof adjacent thereto, of a door provided with hinge straps the ends of which are 5 mounted within said slots and a portion of each of which is bent to fit and conform to the bulb aforesaid, said straps being secured in position by a hinge block filler secured between the door end and the projecting 10 portion of said door hinge strap.

7. The combination with a car floor having a door opening therein, of a reinforcing bar one portion of which is secured to the car bottom adjacent to the said door 15 opening, another portion of said bar being provided with a bulb of substantially circular section integral with the rest of the bar, slots through the body of the bar adjacent to said bulb, a door provided with 20 hinge straps the ends of which pass through the slots aforesaid and each of which is bent to substantially fit and conform to the bulb

aforesaid, and means for maintaining said hinge straps in rotative position on said bulb.

25

8. The combination with a car floor having a door opening therein, of a reinforcing bar one portion of which is secured to the car bottom adjacent to the said opening, another portion of said bar being provided 30 with a bulb of substantially circular section, slots through the body of the bar adjacent to said bulb, a door provided with hinge straps the ends of which pass through the slots aforesaid and each of which is bent 35 to substantially fit and conform to the bulb aforesaid, and a hinge block filler secured between the door end and the projecting portion of said door hinge strap adapted to maintain said strap in rotative position on 40 said bulb.

In witness whereof I hereunto affix my signature.

LOUIS G. MILLER.
